(57) **CLAIM**

The ornamental design for an earphone box, as shown and described.

DESCRIPTION

FIG. 1 is a front perspective view of an earphone box showing our new design;

FIG. 2 is a front view thereof;

FIG. 3 is a back view thereof;

FIG. 4 is a top view thereof;

FIG. 5 is a bottom view thereof;

FIG. 6 is a right view thereof;

FIG. 7 is a left view thereof;

FIG. 8 is a front perspective view of a first component of the earphone box of FIG. 1, shown separately to show aspects of the design that are not visible when combined;

FIG. 9 is a front view thereof;

FIG. 10 is a back view thereof;

FIG. 11 is a top view thereof;

FIG. 12 is a bottom view thereof;

FIG. 13 is a right view thereof;

FIG. 14 is a left view thereof;

FIG. 15 is a back perspective view thereof;

FIG. 16 is a front perspective view of a second component of the earphone box of FIG. 1, shown separately to show aspects of the design that are not visible when combined;

FIG. 17 is a front view thereof;

FIG. 18 is a back view thereof;

FIG. 19 is a top view thereof;

FIG. 20 is a bottom view thereof;

FIG. 21 is a right view thereof;

FIG. 22 is a left view thereof;

FIG. 23 is a back perspective view thereof; and,

FIG. 24 is an exploded front perspective view of the earphone box of FIG. 1, separating the first component of the

(Continued)

earphone box from the second component of the earphone box, and showing the earphone box in an exemplary environment.

The broken lines in the drawings show portions of the earphone box that form no part of the claimed design. The broken lines showing earphones in FIG. 24 depict environmental structure and form no part of the claimed design.

1 Claim, 24 Drawing Sheets
